UNITED STATES PATENT OFFICE.

GEORGE W. HILL, OF STARK'S POINT, WASHINGTON TERRITORY.

FILE-HANDLE.

SPECIFICATION forming part of Letters Patent No. 275,911, dated April 17, 1883.

Application filed July 22, 1882. (Model.)

To all whom it may concern:

Be it known that I, GEORGE W. HILL, of Stark's Point, in the county of Wahkiakum and Territory of Washington, have invented a new and Improved File-Handle, of which the following is a full, clear, and exact description.

My invention consists of a file-handle contrived with attachments for enabling it to be used for jointing, setting, and gaging the teeth of the saw, and also provided with a straight-edge and lineal measure, whereby the combined implement embodies all the necessary devices for enabling the woodman to carry with him the means by which to keep his saw in order, and thus save the labor of carrying it home for the purpose, and back again, as hereinafter described.

Reference is to be had to the accompanying drawings, forming part of this specification, in which similar letters of reference indicate corresponding parts in all the figures.

Figure 1 represents a perspective view of my improved file-handle and attachment, and shows the method of jointing saws with it in dotted lines. Fig. 2 is a side elevation of a portion of the handle, and shows the method of setting the teeth with it in dotted lines; and Fig. 3 is a side elevation of a portion of the handle, and shows the method of gaging the set of the teeth with it in dotted lines.

A represents a handle of suitable size and form for using a file, B, in the ordinary way for filing saws, the tang of the file being inserted in a socket in the end of the handle, and secured by a set-screw, C, or other approved means. I propose to make this handle of metal in order to be substantial and reliable for carrying the attachments which I apply to it, and so that one of its sides, D, may be used for a straight-edge to gage the "rakers," and for the application of a scale of inch-measure, a, for convenience when it is desired to ascertain dimensions of logs and other objects. To the end opposite to the file-socket I apply a setting device consisting of the flat-headed screw E, screwed into and tightly fitting a screw-tapped hole in the end of the handle for adjusting it to saws of different thicknesses, the said head being notched at F for the protection of the points of the teeth.

The method of using the set is represented in Fig. 2, where G represents the saw-plate, and H the tooth being set.

The jointing attachment for truing the points of the teeth consists of the file holders and guides J K, attached to the handle, as shown, or in any other approved way, and having slots L, for reception of the file, and M for the saw-plate G, (dotted,) whereby said holders and guides, being attached to the handle, may have a file, N, (dotted,) attached temporarily for brushing lightly over the points of the teeth to reduce them to uniform length, the file being guided by the saw in the slots M, as clearly shown in Fig. 1.

The setting-gage, by which to regulate the set of the teeth, consists of the stud O and the adjusting-screw P, applied to the handle, to project from one side, as shown. This device is used as represented in Fig. 3, the handle A being placed against the side of the saw G, with the screw projecting to the required extent for gaging the set of the tooth H by the stud O. By shifting the screw P the device may be adjusted for teeth having more or less set. In this case the file holder and guide J is attached by means of a yoke embracing the end of the handle, and made fast by a set-screw, R, the yoke being placed against a stop, S, on the handle, and the holder J is attached by means of a screw-shank, T, screwing into a hole in the side of the handle. The side opposite to D, I propose to have dressed true for a straight-edge, to be used as a gage for the raker-teeth of saws having such teeth, and for any other purposes for which it may be required.

I also propose to make the head E of the saw-set serve for a screw-driver, as shown at E', Fig. 1.

Having thus fully described my invention, I claim as new and desire to secure by Letters Patent—

1. The combination, with a file-holder handle, of the guides J K, each having the horizontal cross-slot L, and connected with the middle thereof, a subjacent vertical slot, M, whereby the points of the teeth may be trued by a brush-file, as described.

2. The file holder and guide J, combined with the handle by a yoke on the upper part of the guide, a screw, R, and a stop, S, on the top of the handle, as shown and described.

GEORGE WOOD HILL.
